[57] CLAIM

The ornamental design for a valve for inflating tires, balloons, or the like, as shown and described.

DESCRIPTION

FIG. 1 is a front elevational view of a valve for inflating tires, balloons or the like showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view thereof, illustrating an example use of the article to inflate a balloon.

The broken line showing of a cartridge in FIGS. 1, 2, 4, 5, and 6 and a cartridge and balloon in FIG. 7 is for illustrative purposes only and forms no part of the claimed design.
